UNITED STATES PATENT OFFICE

DAVID T. WILLIAMS, OF PATERSON, NEW JERSEY

DRIFTING VALVE

Application filed December 31, 1925. Serial No. 78,567.

This invention relates to automatic means whereby, when the driving steam is cut off from a locomotive engine, fluid, as boiler steam, is admitted to the engine, and when the driving steam is allowed to flow to the engine the flow of such fluid is checked, so that under the first of these conditions the known disadvantageous results of the piston continuing to reciprocate in vacuo in the engine cylinder will be avoided. The object is to provide improved means of this class, or what is known as an automatic drifting valve, which shall embody all of the following advantageous features, to wit, efficiency under all conditions, simplicity of construction, and reliability not only in respect to the performance of its principal function but to the end that its incorporation in the equipment of a locomotive shall not introduce any possible element of danger.

I have fully illustrated my invention in the accompanying drawings, in which

Fig. 1 is a side view of a locomotive embodying the improved drifting valve;

Fig. 2 is a fragmentary rear elevation of the boiler, steam turret and one of the steam pipes; and

Figs. 3 and 4 are a vertical central sectional view and an end view of the device.

The locomotive has an engine of usual type, 1 being the cylinder and 2 the steam-chest; 3 is the main steam pipe for super-heated steam leading to the steam-chest, and 4 is a steam turret communicating with the boiler 5 and conveniently placed as usual in the driver's cab.

The drifting valve is indicated generally in Fig. 1 by the character 6. The pipe through which control of the moving part of this drifting valve is effected from the steam-chest (or rather all that space, which I term the working space, which is subject to the suction-action of the piston in said cylinder when the locomotive is drifting with the driving steam cut off) is indicated at 7; it may have a shut-off cock 7^a. The passage to be controlled (i. e., for fluid, as saturated steam, which is to be admitted to the locomotive cylinder when the locomotive is drifting with the driving steam cut off) is afford-

ed by the pipe 8, a cylinder (to be described) of the drifting valve 6, and a pipe 9; pipe 8 leads from the turret 4 to the drifting valve and may contain a reducing valve 8^a (Fig. 2), and pipe 9 leads from the drifting valve to any part of the mentioned working space, as the main steam pipe 3, and it may if desired contain a check-valve 9^a the detail of which is not shown and which it is not material to describe except to say that it closes toward the drifting valve. It is neither necessary nor desirable, of course, that the steam passing to the locomotive cylinder via 8—13—9 should have a pressure as great as that at the source 4, which communicates with the boiler; hence the reducing valve 8^a is provided.

The casing or fixed part of the drifting valve includes a hollow structure 10 having a base 11 and forming two cylinders 12 and 13 axially aligned with and open toward each other, the former (or what I term the major cylinder) being of appreciably greater cross-sectional area than the latter (or minor) cylinder; and heads 14 and 15 bolted to the outer ends of cylinders 12 and 13, there being a space or chamber 12^a between the cylinders. The moving member of the device includes a major piston 16 fitting cylinder 12, an axial stem 17 suitably secured to said piston, and an element here formed in two parts 18 and 19 with a space or deep groove 19^a between them, they being suitably secured to the stem; and part 18 forming a valve to control the aforementioned passage. The major cylinder and piston in effect form a motor for such valve. When the locomotive engine is working the pressure in its mentioned working space acts through a port 7^a with which pipe 7 communicates to hold the moving member of the drifting valve with piston 16 against a stop-flange 16^a and hence the valve in closing relation to the passage; when the locomotive engine is drifting, as the result of the suction developed in said working space, said moving member is shifted to the left, so that valve 18 uncovers the passage from 8 to 9 via space 19^a and said passage is open and boiler steam flows to said working space.

Piston 16 has a port 20 connecting chamber 100

12^x with the space at the left side of the piston, and a check-valve 21 in said port seats toward the latter space and is normally held seated by a spring 22; this spring represents a force much less than that of the pressure of the driving steam and is adapted to yield to such pressure, as when the latter shifts the moving member of the drifting valve to the limit afforded by stop-flange 16^a, whereupon 10 the steam enters chamber 12^x so that as soon as suction is created (on drifting) in the working space of the engine, with consequent reduction of pressure at the left of piston 16, and since the pressure area of piston 16 exceeds that of the valve portion of element 15 18—19, the pressure in chamber 12^x is effective to and does produce a certain and quick movement of the said moving member to open the communication from 8 to 9. 20 There is preferably a vent 23 connecting the outer end of cylinder 13 with the atmosphere; it may be suitably restricted so that the movement of the movable member of the device in each direction will be cushioned. A standardizing of the resistance opposed to the 25 right-hand or valve-closing movement of the moving member is obtained by providing a vent 24 which is closed by piston 16 on such movement but is opened to the atmosphere when said member moves to the left; this vent, 30 and a port 25 in stop-flange 16^a also permit draining chamber 12^x of any condensation.

Valve 18 is cup-shaped, with its open side toward part 19, and its cylindrical wall has 35 radial ports 26 therethrough communicating with an exterior circumferential groove 27 which when the valve is closed registers with a vent 28 leading to the atmosphere.

The action of the device is both quick and 40 certain, not only in the movement to close the passage afforded by 8—13—9 but in the movement to open the same, due to the trapping of steam from the working space of the engine in the chamber 12^x and to the superior area of piston 16 over that of the valve portion of the element 18—19 taken with the existence at 45 this time of suction at the left side of the piston.

The device is entirely proof against accumulation of pressure in the working space 50 of the engine sufficient to start the same inadvertently while standing. If the moving member is at that time in open position the pressure of boiler-steam finding its way through passage 8—13—9 to said space and back through pipe 7 to cylinder space 12 would act to move said member to close off 55 the passage before the pressure would build up in the working space of the engine sufficient to start the same. There will be a venting at 28 of steam entering the casing from 60 said passage if, the moving member being in closed position, there is a leaky condition of the part 18, for instance, if this is due to longitudinal scoring of said part so that the leak-

age would have to pass to one end thereof and then back in order to reach the eduction port 9^x it would be vented since 27—28 intervenes between 9^x and the left-hand end of the part 18 and from the opposite end of said part 70 leakage will be vented via the passage formed by the interior 18^a thereof and ports 26—27—28.

When the moving member is shifted to closed position the pressure at the right of 75 part 18 is not a resisting force because parts 19—18 then trap this pressure. Regardless of the pressure of the part 19, 18^a—26—27—28 serve to vent this pressure at the end of the closing movement of said member.

Any condensation which at times might form in pipe 8 when the valve is closed may 80 find escape into space 19^a by port 29, this port being small enough so that the escape of steam therethrough and to space 19^a and thence via 19^a—18^a—26—27—28 to the atmosphere would be negligible.

Having thus fully described my invention what I claim and desire to secure by Letters Patent is:

1. A drifting valve device for locomotive engines including a cylinder having an eduction port in its cylindrical wall forming with said cylinder a part of a passage for conducting fluid to the working space of the engine while the locomotive is drifting and a valve movable lengthwise of and in the cylinder to close off said passage, said device having means for venting from the cylinder fluid entering the latter when the valve is closed including a groove surrounding the valve at one side of said eduction port and a passage extending from said groove to the end of the valve at the other side of said port.

2. In a drifting valve device for locomotive engines, the combination of a passaged structure for conducting steam to the working space of the engine including a cylinder, and a valve movable in the cylinder to close off from the latter the part of the passage leading thereto, said device having means, closed by the valve when the latter is open and extending through the valve, for venting to the atmosphere when the valve is closed 115 condensation then accumulating in said part of the passage.

3. In an apparatus of the class described, the combination of a casing having aligned major and minor cylinders and a chamber 120 intervening between them and communicating with the major cylinder, the minor cylinder having an inlet adapted to be connected with a steam source and an outlet adapted to be connected with a locomotive steam chest, a piston in the major cylinder, a valve in the minor cylinder to control steam flow through the latter from the inlet to the outlet, said piston and valve being movable longitudinal- 125 ly of the cylinders as a unit and the major 130

cylinder having its outer end closed and also having an inlet to admit fluid from the steam chest to the space between said end and the piston whereby to move the latter and hence
5 the valve in one direction, a check-valve means to permit a part of the fluid entering said space from the steam chest to pass the piston and enter and become trapped in said chamber, and means to vent said chamber on
10 exhaust of the fluid from said space and consequent return movement of said piston and valve.

In testimony whereof I affix my signature.
DAVID T. WILLIAMS.
